Patented June 4, 1918.

Inventor
GRANT E. ALLEMAN,

By Attorney

UNITED STATES PATENT OFFICE.

GRANT E. ALLEMAN, OF SHOEMAKERSVILLE, PENNSYLVANIA.

COAL-WASHING TROUGH.

Specification of Letters Patent.

Patented June 4, 1918.

1,268,531.

Application filed August 25, 1917. Serial No. 188,098.

To all whom it may concern:

Be it known that I, GRANT E. ALLEMAN, a citizen of the United States, residing at Shoemakersville, in the county of Berks and State of Pennsylvania, have invented certain new and useful Improvements in Coal-Washing Troughs, of which the following is a specification.

This invention relates to improvements in coal washing troughs and it is intended more particularly for use in connection with a dredging or coal reclaiming device, in which the culm is drawn up from the river bed and the coal washed from the culm so procured.

The invention consists of a trough provided with a series of retarding pockets, whereby the water is prevented from passing through the trough too rapidly, and with a screen over which the coal passes while it is subjected to the washing effect of the water.

The invention is more fully described in the following specification and clearly illustrated in the accompanying drawing, in which:

Figure 1 is a plan view of my improved trough, with a portion of the screen broken away for the purpose of better illustration.

Fig. 2 is a longitudinal sectional view, taken on the line 2—2 of Fig. 1.

The numeral 1 designates the two, parallel, longitudinal side members of the trough, while the numerals 2 and 3 designate a series of approximately vertical and inclined wall members respectively, alternately ar-

ranged, and the numeral 4 designates a series of base members. These members 2, 3 and 4 extend the full width of the trough, between the side members 1, and form a series of pockets 15, each of which is provided with

an inclined and a vertical wall, and the base members are each formed with a plurality of perforations 5.

Along the inner side of each wall member 1, and lying directly on the tops of the members 2 and 3, I place a strip 6, and on this strip I secure a screen 7, extending the full inner width of the trough. The receiving end of the trough is indicated by the supply nozzle 20, and the delivery end is formed with an enlarged pocket 8, provided with a suitable cover 9 and this pocket is provided with a relatively large outlet 10 in its bottom, from which depends a tubular member 11.

In use, the material to be washed is deposited from the nozzle 20 into the receiving end of the trough, and the larger particles

of coal will ride along the upper surface of the screen, and this end of the trough is raised, relatively to the discharging end, so as to secure the desired "drift", the angle 60 depending on the nature of the culm deposited therein.

During the passage of the culm through the trough, the water will pass through the screen, together with the refuse or smaller 65 particles, and these smaller particles will find their way through the perforations 5, together with a small portion of the water, while the greater portion of the water will pass along from one pocket to another, down 70 the inclined walls and over the vertical walls, where it will pass through and wash the coal drifting along the surface of the screen, so that by the time the coal reaches the end of the trough and is deposited in the 75 larger pocket 8, it will be thoroughly cleansed, and will pass out through the tube 11, which may be connected to any suitable delivery device.

It is evident that the inclined walls on the 80 rear sides of the pockets, that is, those toward the feed end of the trough, will receive and divert the downflowing streams, the diversion being completed by the approximately vertical walls which return the 85 liquid upwardly through the screen at approximately a right angle thereto, and therefore with the strongest impetus for separating purposes obtainable for a flow of the nature employed, and which impetus would be 90 much less were the forward walls to have a sloping inclination. The discharge openings 5 of each pocket obviously must have a capacity to discharge substantially less than the total of material and liquid reaching the 95 pocket.

This construction, whereby the water is retarded in its passage, will insure the removal from the coal of all mud and other objectionable soluble matter.

The cover on the pocket 8 will prevent the coal from "spraying" or being thrown out of the trough.

I have shown a refuse chute, 21, attached to the side members 1 of the trough by 105 means of hangers 22 and extending longitudinally beneath the trough, so that if desired, the refuse may be directed to any desired point. This chute is inclined relatively to the trough, and when the trough is placed 110 in inclined position, this chute will always shed the refuse at a greater incline than that

of the trough, to prevent clogging. This chute may also be provided, as shown, with a tubular outlet 23, for connection with any suitable delivery device.

5 What I claim is:—

A washing trough consisting of an inclined screen-bottomed trough, pockets below the trough, said pockets having inclined

rear and vertical forward walls whose upper edges reach to the screen, said pockets having restricted discharge openings in the bottoms thereof, and means for feeding material suspended in liquid to the higher end of the trough.

In testimony whereof I affix my signature.

GRANT E. ALLEMAN.
